(57) **CLAIM**

The ornamental design for a set of muscle stimulator and charging case as shown and described.

DESCRIPTION

FIG. 1 is a perspective view of a muscle stimulator of a set of muscle stimulator and charging case showing my new design, shown separately for ease of illustration;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of a charging case of the set of muscle stimulator and charging case, shown separately for ease of illustration and in a closed configuration;

FIG. 10 is another perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof;

FIG. 16 is a bottom plan view thereof; and,

FIG. 17 is a perspective view of the set of muscle stimulator and charging case, shown in use with the muscle stimulator received in the charging case and in an open configuration. The broken lines in the drawings are for the purposes of illustrating portions of the set of muscle stimulator and charging case, which form no part of the claimed design.
